UNITED STATES PATENT OFFICE.

FRANK E. LAYMAN, OF MILWAUKEE, WISCONSIN, ASSIGNOR TO THE CUTLER-HAMMER MFG CO., OF MILWAUKEE, WISCONSIN, A CORPORATION OF WISCONSIN.

MOLDED HANDLE AND THE LIKE.

Application filed May 5, 1922. Serial No. 558,746.

This invention relates to molded handles and the like, and while not limited thereto is particularly applicable to handles for hollow ware articles.

- 5 Handles for such use have heretofore been constructed ordinarily either of bakelite or of wood whereas both of said substances possess serious disadvantages for the purpose. Thus while bakelite possesses adequate strength and other desirable properties, the cost of producing and forming the same is so high as to curtail seriously its applicability and to increase inordinately the cost of the articles to which it is applied, 10 whereas the use of wood for the purpose is disadvantageous owing, among other causes, to its low heat and combustion resistive characteristics and inferior appearance.

The present invention has among its objects that of providing handles for the afore indicated and other uses, wherein such disadvantages are obviated or materially reduced.

Another object is that of providing handles for the purposes mentioned possessing substantially the durability, finish and other desirable characteristics of bakelite at costs not greatly exceeding that of the undesirable wood handles.

30 Another object is that of providing molded handles of pleasing appearance and possessing marked electrical insulating and heat insulating and resisting properties combined with ample mechanical strength for performance of their usual and intended functions and also having certain special features adapting the same to maintain their usefulness and substantially their original appearance for indefinite periods of 35 service although such service may involve serious accident or mishandling.

Other objects and advantages will hereinafter appear.

In the accompanying drawing, wherein 45 are illustrated certain of the embodiments which the invention may assume in practice,

Figure 1 is a side elevational view of a given construction thereof; while,

Figs. 2, 3 and 4 are similar views showing slightly modified constructions.

In practice it is proposed to form the handle of one or another of the well known moldable insulating compounds, preferably one capable of formation by a quick molding process, which substances when properly molded and cured ordinarily possess ample mechanical strength for ordinary uses of the handle, together with the other desirable characteristics aforementioned, and to incorporate within the handle, at the time of forming, a suitable tie member or trellis whose function is to maintain the shape, strength and appearance of the handle following possible strain or cracking of the molded material thereof, said tie member 60 or trellis being in practice preferably terminally anchored to and within the terminal portions of the handle.

Referring to Fig. 1 of the drawing, the same illustrates a percolator or other hollow ware article handle formed and constructed in the manner herein contemplated. The handle itself is essentially of reflexed structure comprising a substantially horizontal body portion 5 of relatively large 70 dimensions, a tapered downwardly extending portion 6 making approximately a right angle with the portion 5 and terminal portions 7 and 8 providing for securement of the handle to the hollow ware article. In 75 practice such article may be provided, as illustrated, with upper and lower stirrups 9 and 10 to receive the respective terminal portions 7 and 8 of the handle, the individual stirrups and their respective associated handle terminal portions being provided with registering holes each to receive a rivet 11 or the like for permanent securement of the handle to the article.

80 A tie member or trellis 12 is formed within the handle to extend throughout or substantially throughout the longitudinal extent thereof. In practice the tie member is preferably formed with terminal loops or eyes 13 formed by reflexing the terminal portions of the tie member and twisting the same about the main portion of the tie member, or soldering the same thereto, or both. The loops 13 are so arranged as to surround 85 the aforescribed rivet holes in the handle, 90

95

100

whereby upon mounting of the handle the tie member is permanently anchored terminally to the rivet or other handle securing means, whereas the terminal enlargement of the tie member incident to formation of the loop provides for inherent anchoring of the tie member within the molded material of the handle.

Thus it is to be observed that in case of accident or other mishandling of such severity as to cause cracking of the molded material of the handle the tie member 9 is nevertheless adapted itself to maintain substantial continuity of the cracked sections whereby even following very serious cracking the utility and even the appearance of the handle and of the article to which the same is secured are not in any serious respect impaired, whereby the life of the handle may be prolonged practically indefinitely even following such fracture or cracking of the molded material thereof as in the absence of the tie member would necessarily result in discarding the handle and probably the complete device owing to the well known difficulty of replacement.

The construction illustrated in Fig. 2, while in general similar to that described, differs therefrom in the specific character of the securing means employed.

In this construction the terminal portions of the handle are provided with in-molded inserts which may comprise respectively an externally threaded stud 15 and an internally threaded thinble or socket 16 to terminate preferably substantially flush with the adjacent surface of the handle. Said inserts are provided individually with suitable shoulders 17 about which the terminal portions of the tie member 12 are looped and anchored in a manner similar to that aforescribed. In this instance the reflexed portions of the tie member are preferably soldered to the main body thereof, 45 which soldering connection may include the inserts if desired.

The construction of Fig. 3 is practically similar to that of Fig. 2 except that in the former both metallic inserts are adapted to project beyond the respective ends of the molded portion of the handle. Such projecting portions of the inserts constitute in effect reduced lugs or extensions 18, 19 adapted to take within suitable sockets 20, 55 21 of the hollow ware article and being in practice permanently cemented or similarly secured therein.

In the construction shown in Fig. 4, the aforementioned lugs are provided by means of reduced portions 22, 23 of the molded material of the handle, such reduced portions subserving functions similar to those of the inserts 18, 19 of Fig. 3. In this construction the terminal portions of the tie

member are arranged to extend substantially through and centrally of such reduced terminal portions of the handle, being therewith preferably enlarged, roughened, corrugated or otherwise rendered superficially irregular for secure anchoring of the tie member within such terminal portions of the handle and also within the sockets to which the handle is secured.

The material constituting the bulk of the handle may comprise in practice practically any of the well known molding compounds heretofore employed in the production of electrical insulation and analogous articles, such compounds as a class being characterized by high heat resistive properties and superior finish of the articles formed thereof. The operation of forming the handle aside from incorporation of the tie member may be in all essential respects similar to that ordinarily employed in treating the particular substance used.

The tie member may be preferably metallic in character and is preferably of such composition as to afford considerable rigidity, toughness and also preferably slight resiliency. In practice ordinary iron wire of suitable size may be employed or where extreme lightness is desired aluminum may be substituted advantageously, whereas other substances also may be employed.

What I claim as new and desire to secure by Letters Patent is—

1. The combination with a reflexed elongated molded handle formed of heat resistive plastic composition material, of a reinforcing element entirely embedded therein and extending throughout the major portion of the length thereof, and members embedded in the terminal portions of said handle and anchored to said reinforcing element to provide for attachment of said handle to an article.

2. The combination with a handle formed of plastic composition heat insulating material, of a reinforcing wire of relatively small cross section entirely embedded therein and extending between the opposite terminals thereof, said wire having a loop at each end thereof, and metallic members surrounded by said loops and embedded in the respective terminals to provide for attachment of said handle to an article.

3. A handle for a hollow ware article, comprising insulating and heat resistive plastic composition material molded into an elongated reflexed shape, a relatively thin wire permanently embedded within said handle, said wire having a terminal anchoring loop within each terminal portion of said handle, and means cooperating with certain of said terminal portions to detachably secure said handle to said article.

4. A handle for a hollow ware article,

comprising insulating and heat resistive plastic composition material molded into an elongated reflexed shape, a tie member of relatively small cross section molded within 5 said handle and extending between the terminal portions of the latter, means secured to said tie member adjacent each of said

terminal portions for engaging cooperating portions of the article, and means associated with one of said terminal portions for securing all of said portions in engagement. ¹⁰

In witness whereof, I have hereunto subscribed my name,

FRANK E. LAYMAN.
